UNITED STATES PATENT OFFICE.

JOHN B. DAVIS, OF SPRINGFIELD, MASSACHUSETTS, ASSIGNOR TO GILBERT & BARKER MANUFACTURING COMPANY, A CORPORATION OF MASSACHUSETTS.

DISPENSING PUMP.

Application filed November 7, 1921. Serial No. 513,369.

To all whom it may concern:

Be it known that JOHN B. DAVIS, a citizen of the United States, residing at Springfield, in the county of Hampden, and State of Massachusetts, has invented new and useful Improvements in Dispensing Pumps, of which the following is a specification.

The present invention relates to improvements in dispensing pumps such as are commonly used for dispensing measured quantities of gasoline or like liquids.

In one aspect, the invention relates more particularly to quantity stops for pumps of the general type above described and contemplates the provision of novel means whereby the stops may be selectively positioned to predetermine the amount of liquid to be delivered by the pump.

One object of the invention is to provide, in a measuring pump provided with quantity stops for limiting the stroke of the pump piston and having a casing enclosing said stops and the supporting structure therefor, means operable from the exterior of the casing for moving the stops into and out of working position.

Another object of the invention is to provide, in connection with the above mentioned quantity stop actuating means, an enclosing casing or housing for the quantity stops constructed and arranged to facilitate the connection of said stops and their actuating means.

Other objects of the invention, together with the features of construction by which they are attained, will be apparent from the following description of the preferred embodiment thereof, illustrated in the accompanying drawings, in which:

Fig. 1 is a view, in front elevation, of a dispensing pump constructed in accordance with the invention;

Fig. 2 is a fragmentary view, in rear elevation, of the pump shown in Fig. 1;

Fig. 3 is a view, in sectional elevation, partly broken away, of the upper portion of the pump, showing particularly the quantity stops;

Fig. 4 is a fragmentary elevational view, on an enlarged scale, showing in detail the construction of one of the quantity stops;

Fig. 5 is a sectional view taken on the line 5—5 of Fig. 1;

Fig. 6 is a fragmentary view, partially in side elevation and partially in vertical section, showing certain features of the pump actuating mechanism;

Fig. 7 is a plan view on an enlarged scale of the braking device for retarding or stopping the operation of the pump; and

Fig. 8 is a sectional view taken on the line 8—8 of Fig. 7.

In the drawings, the invention is illustrated as embodied in a power-operated dispensing pump of the type disclosed in the inventor's prior U. S. Letters Patent No. 1,447,511, granted March 6, 1923. In general this pump comprises the usual pump cylinder 10 (Fig. 6), its piston (not shown) and piston rod 12; a cross-head 14 carried by the piston rod 12; a pair of vertical operating rods 16 connected at their upper extremities to the opposite ends of the cross-head and carrying pistons (not shown) at their lower extremities; compressed air cylinders 18 for the operating pistons; a horizontal shaft 20 having a pair of gears 22 fixed thereon and meshing with rack teeth on the backs of the operating rods 16 for constraining said rods to move in unison; a casing enclosing the above mentioned parts comprising a cylindrical body portion 24 (Figs. 1, 2 and 6); a cover 26 having a central elliptical opening 28 for the passage therethrough of the cross-head 14, and an upright casing or housing 30 extending above the cover 26 and within which the quantity stops and the supporting structure therefor are located; a discharge pipe 32 (Fig. 1) leading from the pump cylinder and rising through the cover 26; and means including a crank handle 34 carried at one end of the shaft 20 which projects outside of the pump casing and is adapted to be clutched to said shaft to enable the pump actuating mechanism to be manually operated when so desired. It should be understood that through the agency of suitable connections and a single control valve compressed air or other fluid under pressure is adapted to be admitted beneath the pistons in the cylinders 18 or exhausted from said

cylinders at the will of the operator of the pump. Upon the admission of air to the operating cylinders 18, the operating rods 16 are raised to actuate the pump through its suction stroke while the exhaustion of the air from said operating cylinders permits the pump piston, which is heavily weighted, to be returned by gravity into position for the start of another suction stroke.

10 With the exception of the casing or housing 30, all the above named elements are or may be of the same construction and all the moving parts above described operate in the same manner as corresponding parts disclosed in the above mentioned prior patent and, inasmuch as the present invention is independent of the particular construction and operation of these elements, further description thereof is considered 15 unnecessary in this application. The housing 30, however, embodies in its construction, certain features of the present invention and will be hereinafter fully described.

In order that the pump may be set to 20 deliver different predetermined quantities of liquid, a series of quantity stops 38 are provided which are adapted to be selectively positioned to limit, in different degrees, the stroke of the pump piston. The construction 25 of the quantity stops and the manner in which they are mounted upon the pump is substantially the same as that disclosed in the inventor's U. S. Letters Patent No. 1,449,218 granted March 20, 1923. Consequently it will not be necessary to describe 30 in detail the common features of the two sets of stops, reference being made to said application for a complete disclosure thereof.

40 Briefly set forth however, the quantity stops 38 comprise fingers carried by an inverted U-shaped standard 40, the upright legs of which are rigidly secured at their lower ends to a circumferential flange 42 such as usually surrounds and defines the 45 elliptical opening 28 in the casing cover 26, the arrangement being such that the cross-head 14 will travel between the arms of the standard as the pump piston reciprocates.

50 The stop fingers 38 are adapted to be positioned at will across the path of the reciprocating cross-head and to this end the fingers are pivotally mounted, one above another, upon a single vertical rod 44 that is rigidly supported in front of one leg of the standard 40. The pivot rod 44 extends through a plurality of ears 46 projecting from the standard 40, the ears being arranged in pairs and the stop fingers are 55 severally mounted between the individual members of said pairs. Normally the stop fingers are inoperatively positioned as indicated by full lines in Fig. 5 and in order that they may be operatively positioned in 60 the path of the cross-head 14, the fingers

are severally adapted to be swung to bring their free extremities into engagement with the opposite leg of the standard 40 from that upon which they are pivotally mounted. To frictionally hold the stop fingers in adjusted positions each finger is acted upon by a spring 48 (Fig. 4) which encircles the pivot rod 44 between the finger and the ear 46 immediately beneath the finger. To insure accuracy of measurement of the liquid dispensed by the pump a stop screw 50 is threaded vertically through each stop finger at such a point that when the finger is set in operative position, as indicated by dash lines in Fig. 5, said screw will be located in vertical alinement with the central portion of the cross-head 14 and will thus constitute an adjustable limiting stop for determining the stroke of the pump piston. Locking pins 52 carried by the stop fingers prevent accidental turning of the stop screws after they have been initially adjusted and suitable means may be provided for sealing the locking pins to prevent unwaranted interference with the adjustment of the stop screws.

As so far described, the construction and mode of operation of the quantity stops is, in all respects, substantially the same as that set forth in the last named patent. The standard 40 of the present apparatus, however, differs in several important particulars from that disclosed in said application. In accordance with the present construction, the two legs of the standard severally comprise flat elongated bars 54 and 55 (Figs. 3 and 5) having central longitudinal strengthening ribs 56 projecting from both sides of said bars at right angles thereto, and each bar being further provided at one end with inwardly turned ears 58 and at the opposite end with feet 60 which are curved slightly to conform to the inside curvature of the flange 42 on the casing cover. The two bars 54 and 55 are cast separately and 100 are connected, at their upper ends by means of a cross-bar 62 which is bolted to the ears 58, as shown in Fig. 3. The feet 60 are, in turn, bolted to the flange 42 of the casing cover.

To prevent upward or other yielding displacement of any of the stop fingers 38, while engaged by the cross-head 14, provision is made for reinforcing the stop fingers at their free extremities. To this end, in accordance with the present invention, the strengthening rib 56 at the inner side of the bar 54 is made wider than the rib on the outer side of said bar, as shown in Figs. 3 and 5, and the wide rib 56 is provided with a plurality of notches 64 which are so located that one notch will be opposite each stop finger 38 when the latter are assembled in the apparatus. Each stop finger 38 is cut away at its free extremity, as indicated at 115

in Fig. 5 to permit the finger to swing into the respective notch 64 and to provide a projection 68, which is adapted to engage the face of the notched rib 56 and thus to limit the swinging movement of the stop finger when it has reached the position shown by dash lines in Fig. 5. When thus positioned, the upper face of the stop finger engages a shoulder formed by the upper edge face of the notch 64 and the latter reinforces the free end of the stop finger so as to positively prevent upward movement thereof when engaged by the cross-head 14. The bar 54 may conveniently be cast with the notches 64 formed therein and, if necessary, the upper edge faces of said notches may be machined after the parts of the standard 40 have been assembled so that said edge faces will be accurately located with respect to the stop fingers. By constructing the standard 40 in three separate parts and by notching one of said parts to provide reinforcing shoulders for the stop fingers, the operation of casting the standard is materially simplified. As shown, a stop screw 66, similar to those carried by the several stop fingers may be threaded through the cross-bar 62 at the top of the standard 40 to cooperate with the cross-head 14 to determine the maximum stroke of the pump piston.

In the present apparatus the standard 40 together with the quantity stops mounted thereon is enclosed within a housing 30, as already described. To enable the quantity stops to be selectively positioned without the necessity of removing or opening the housing 30 the quantity stops are severally operatively connected with a series of buttons 70 (Figs. 2 and 5) which are mounted one above another in spaced relation in the side of said housing. As shown in Fig. 5, each button 70 is secured to one end of a wire rod 72 which extends substantially horizontally through an aperture in the housing and is pivotally connected at its opposite or inner extremity to one of the stop fingers 38.

As shown, the innermost portion of the wire rod 72 is bent to provide a substantially vertical extremity 74 (Fig. 4) which is laterally offset from the rest of the rod to enable it to project through a hole in the stop finger near the pivoted end of the latter. When the stop fingers occupy their normal inoperative positions, the buttons 70 will be held closely in contact with the outside of the housing 30, as shown in Fig. 5. By pulling the buttons 70 outwardly the stop fingers may readily be swung into operative position to cooperate with the cross-head 14, and the stop fingers may as readily be returned to inoperative positions by merely pushing the buttons 70 inwardly.

The housing 30 encloses the standard 40 together with the quantity stops and is of elliptical cross-sectional contour correspond-

ing to the contour of the flange 42 on the casing cover 26. A cap 76 is provided for closing the upper end of the housing 30. To enable the quantity stop operating rods 72 to be connected with their respective stop fingers, the housing 30 is made, as shown, in four longitudinal segments, comprising two relatively wide side pieces 78 and two relatively narrow end pieces 80 and 82. The segments 78 are curved transversely to fit the sides of the circumferential flange 42 while the end segments 80 and 82 are curved to fit the ends of said flange and all of said segments are securely fastened at the lower ends to the flange. The cap 76 is provided with a depending elliptical flange 84 which is of the same size as the flange 42 and to which the upper ends of the housing segments are secured. The housing segments are designed to be joined together in overlapping relation. The end segments 80 and 82 are preferably arranged with their vertical edges overlapping the adjacent vertical edges of the side segments 78, as shown in Fig. 5, inasmuch as such an arrangement affords better joints between the segments. It is obvious that in assembling the parts of the housing 30, the end segment 82 need not be assembled until after the side segments and the opposite end segment 80 have been in place, thus permitting the workman to reach in through the open end of the housing conveniently to insert the inner ends of the rods 72 in the holes formed to receive them in the stop fingers 38. As shown in Figs. 5 and 6, one of the operating rods 16 is extended above the cross-head 14 to carry a pointer 86, and the end segment 82 of the housing 30 is provided with a longitudinally extending slot 88 through which said pointer extends to cooperate with a scale plate 90 on the exterior of said segment and thus to indicate the quantity of liquid to be delivered by the pump. The cross-head 14 is preferably provided with a post 91 (Figs. 3 and 6) which rises from its central portion to engage the stop screws 50 on the quantity stop fingers 38.

In operating the described pump by power, through the agency of the compressed air cylinders 18, the pump piston moves substantially uniformly throughout its stroke from the time the power is applied to the cylinders 18 until it is disconnected therefrom, as is usual in all power-operated dispensing pumps so far as the inventor is aware. This arrangement has a disadvantage over hand-operation where the pump piston may be controlled to move as slowly as desired. Thus it frequently happens that the purchaser wishes to fill a tank and yet is doubtful whether the tank will hold the entire quantity dispensed at one stroke of the pump. In such cases the purchaser naturally watches the tank and

as it becomes nearly full instructs the operator of the dispensing pump to pump slowly and to be ready to stop at an instant's notice. With the power operated pump as generally provided the above condition can not be met and there is danger of overflowing the tank.

In accordance with the present invention means is provided for controlling the speed of the pump piston while the latter is being operated by power so that the speed of the pump may be retarded as and when desired or, if necessary, stopped altogether before it has completed its full stroke. The means for controlling the speed of the pump piston as above indicated consists of the braking device illustrated in Figs. 7 and 8. The device therein shown consists of a drum 92 fixedly secured to the shaft of the pump, a brake shoe 94 for cooperating with the drum 92 and means for applying the shoe to the drum. For convenience in assembling the drum upon its shaft the drum is made on two parts divided along an axial plane and clamped together and to the shaft by bolts 96. To provide a maximum area of braking surface, the drum 92 is provided with a deep peripheral groove 98, while the brake shoe is formed with a segmental rib 100 the opposite sides of which are adapted to frictionally engage the side walls of the groove 98. The side walls of the groove 98 are inclined toward the base of the groove and the side walls of the brake shoe rib 100 are similarly inclined to cooperatively engage the walls of the groove. No portions of the brake shoe 94 other than the inclined side walls of the rib 100 are adapted to engage with the brake drum and consequently the corresponding inclined portions of the rib and groove will be brought into cooperative relation by the application of pressure to the outer periphery of the brake shoe.

The means for applying pressure to the brake shoe so as to set the brake comprises a lever 102 which is fulcrumed on a stud 104, the latter projecting from a bracket 106 (Fig. 6) which serves to guide one of the operating rods 16 of the pump actuating mechanism. The fulcrumed end of the brake shoe operating lever 102 is forked, as shown, to embrace a pair of lugs 106' which project from the outer periphery of the brake shoe and which in turn embrace the fulcrum stud 104 and serve to position the brake shoe radially with respect to the drum 92 and prevent displacement of the shoe. The forked lower extremities of the lever 102 are provided with cam faces 108 which are adapted to cooperate with flattened faces 110 on the brake shoe to force the latter into engagement with the brake drum. Normally the lever 102 is held in its inoperative position and the brake shoe is maintained disengaged from the brake drum by means of a coil spring 112 which

is secured at one end to the brake shoe and at its opposite end to the lever 102.

When operating the pump by power, the operating rods 16 and the pump piston will be raised at a substantially uniform speed. At the same time the shaft 20 and the brake drum 92 are set in rotation. In case the operator is instructed to pump slowly he simply depresses the lever 102 until the operating rods 16 and the pump piston are retarded to the desired degree and if necessary the pump piston may be entirely stopped by the action of the braking device. In any event the braking device permits the operator to control the speed of the pump piston as and when desired, and particularly according to the desire of the purchaser, whereas without such device it is very difficult to obtain the result desired. At best only an approximation of the result can be obtained by a series of stops and starts and the operator does not have complete control of the situation at all times as he does when the braking device above described is employed.

The braking device is not claimed herein but forms the subject matter of a divisional application Serial No. 643,084, filed June 2, 1923.

The invention is not limited to the use of the particular braking device above described for the purpose of retarding the speed of the pump piston inasmuch as various other means may be provided for this purpose and also such means may be used with various other types of power operated pumps without departing from the spirit of the invention. With regard to its other aspects the invention is not limited to the particulars of construction and arrangement herein shown and described inasmuch as the same may be variously changed or modified within the scope of the appended claims.

I claim:

1. In a measuring pump, the combination with the pump cylinder, its piston and actuating mechanism, of a quantity stop movable into position to cooperate with said mechanism to limit the stroke of the piston, a casing enclosing said actuating mechanism and said quantity stop, a rod extending through an opening in the side wall of said casing and pivotally connected at its inner end with said stop, and a button secured to the rod outside of said casing whereby the rod may be actuated to move said stop into or out of operative position.

2. In a measuring pump, the combination with the pump cylinder, its piston and a member reciprocable with the piston, of a plurality of quantity stops any one of which may be positioned in the path of said member to limit the stroke of the piston, a casing enclosing said member and said stops, a plurality of buttons upon the exterior of the

casing corresponding in number to the number of the quantity stops, and rigid means severally connecting said buttons and stops whereby the former may be actuated to operatively or inoperatively position the latter.

3. In a measuring pump, a member reciprocable with the pump piston, an inverted U-shaped standard rising from the pump body, a plurality of stop-fingers pivotally mounted at one end upon one leg of the standard for independent swinging movement and adapted to be positioned across the path of said member to limit the stroke of the piston, and a plurality of stop shoulders formed by providing notches in the other leg of said standard into which notches the free ends of said fingers are adapted to extend whereupon said shoulders will reinforce said fingers to prevent upward displacement of the latter by said member.

4. In a measuring pump, a member reciprocable with the pump piston, an inverted U-shaped standard rising from the pump body, stop shoulders formed by providing notches in one leg of the standard, a plurality of stop-fingers pivotally mounted at one end upon the other leg of said standard for independent swinging movement and adapted to be positioned across the path of movement of said member to limit the stroke of the piston, said fingers being shaped at their free extremities to enable a portion thereof to be engaged by said stop shoulders for the purpose of reinforcing the fingers against upward displacement by said member while another portion of said fingers engages said leg to limit the swinging movement of said finger to operatively position the latter.

40 5. In a measuring pump, the combination with the pump cylinder, its piston and actuating mechanism, of a member reciprocable with said piston, a casing enclosing said parts and having an opening for the passage therethrough of said member, a circumferential flange surrounding said opening, a standard including a pair of upright bars secured at their lower ends to said flange, a cross-bar bolted to said upright bars to connect their upper extremities, a plurality of stop fingers pivotally mounted at one end upon one of said bars for independent swinging movement and adapted to be positioned across the path of said member to limit the

stroke of the piston, and means on the other of said bars for reinforcing said fingers when operatively positioned to prevent upward displacement thereof by said member.

6. In a measuring pump, the combination with the pump cylinder, its piston and a member reciprocable with the piston, of a plurality of quantity stops any one of which may be positioned in the path of said member to limit the stroke of the piston, a casing enclosing said pump cylinder and having an opening at its upper end for the passage therethrough of said member, a flange on said casing surrounding said opening, a housing rising from said casing and secured at the lower end to said flange, said housing having a transverse curvature conforming to the contour of said flange and said housing comprising a plurality of vertically extending segments having their longitudinal edges overlapped, rods extending through one of said casing sections and severally connected at their inner ends with said stop fingers, and buttons secured to the opposite ends of said rods outside of the casing whereby the rods may be actuated to operate said stop fingers.

7. In a dispensing apparatus, a reciprocating piston pump having a piston rod extending vertically upward through one end thereof, a cross-head fixed to the piston rod, operating rods fixed to and depending from the cross-head on opposite side of the piston rod, means for actuating said operating rods to move the piston rod, and means for enclosing the latter and said operating rods in their reciprocating movement comprising a dome surmounting said end of the pump and having an elliptical opening therein encompassed by an elliptical flange, a member spaced above the dome and having a similar opening and flange, oppositely disposed plates having a curved cross-section of relatively large radius connecting said flanges and enclosing the space therebetween except for relatively small openings at opposite ends thereof, and strips having a curved cross-section of relatively small radius extending between said flanges to close the last-named openings and overlap the edges of said plates.

In testimony whereof I have affixed my signature.

JOHN B. DAVIS.
